UNITED STATES PATENT OFFICE

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS

PRESSER FOOT FOR SEWING MACHINES

Application filed September 17, 1928. Serial No. 306,380.

The invention relates to new and useful improvements in a presser foot for sewing machines, and more particularly to a presser for a sewing machine adapted to make a flat seam.

An object of the invention is to provide a presser foot for sewing machines having a guiding channel for guiding the upturned edge portions of fabric sections for trimming and means for turning said trimmed edge portions into flat lapped relation to each other with a yielding section at one side of the channel which is pivotally attached to the shank of the presser foot so that the fabric engaging portion of said section is capable of a substantially uniform yielding movement in a vertical direction.

A further object of the invention is to provide a presser foot of the above type wherein the stitch fingers are capable of vertical movement.

A further object of the invention is to provide a presser foot of the above type having a yielding section in rear of the needle which extends all the way across the presser foot.

These and other objects will in part be obvious and will in part be hereinafter more fully disclosed.

In the drawings which show by way of illustration one embodiment of the invention:

Fig. 1 is a plan view of a presser foot embodying the invention.

Fig. 2 is a bottom plan view of the same.

Fig. 3 is a side view of a presser foot showing the attachment to the presser bar and the guide bar.

Fig. 4 is a diagrammatic view on the line 4-4 of Fig. 1, and showing the position of the parts when the fabric sections are of uniform thickness.

Fig. 5 is a view similar to Fig. 4 but showing the position of the parts with the fabric sections of greater thickness at the left of the channel in the presser foot.

Fig. 6 is a view similar to Fig. 4, but showing the position of the parts with the fabric sections at the right of the channel of greater thickness.

Fig. 7 is a sectional view on the line 7-7 of Fig. 1.

Fig. 8 is a side view of a presser foot of a slightly modified form of construction.

Fig. 9 is a plan view of the presser foot 55 shown in Fig. 8.

The invention is directed to a presser foot for sewing machines wherein the fabric sections are trimmed, then overlapped and secured by a covering stitch forming mechanism, thus forming a substantially flat seam. The presser foot is provided with a channel which receives the upturned edge portions and directs the same to trimming devices. In rear of the trimming devices there is means for turning the edge portions into flat lapped relation prior to the stitching of the same. The section of the foot at one side of the channel is pivoted to the shank of the presser foot at a point between the attachment of the presser foot to the presser bar and the guide bar. This section is yieldingly depressed so that the bottom of the yielding section may be positioned either above or below the plane of the bottom of the remaining portion of the presser foot. The stitch fingers are mounted so that they yield. The rear portion of the presser foot is provided with a yielding section extending all the way across the foot.

Referring more in detail to the drawings, the presser foot includes a shank portion 1 which is adapted to be attached to a presser bar 3 and a guide bar 2 which are of the usual construction. The shank portion 1 carries a rigid foot portion 4. Attached to the shank of the presser foot is a yielding section 5 and this yielding section 5 is spaced from the rigid foot portion 4 so as to provide a channel 6. The upturned edge portions of fabric sections are directed into this channel. In Figs. 4 to 6 of the drawings, the fabric sections are indicated at F, F', and the upturned edge portions at f, f'. Attached to the rigid foot portion of the presser foot is a stationary trimming blade 7. Cooperating with this stationary trimming blade 7 is a movable trimming blade 8. The upturned edge portions are directed to these trimming devices and are trimmed after 100

which the edge portions are turned down into flat overlapping relation. The left hand edge portion is preferably first turned down after which the right hand portion is turned down onto the left hand portion. The needle passes into the opening 9 and there are preferably a plurality of needles set abreast with which a single looper cooperates beneath the work support. A cross thread laying mechanism cooperates with the needles above the presser foot, and thus it is that a covering stitch is formed.

The yielding section 5 is rigidly connected to an arm 10 which extends along the side 15 of the shank portion of the presser foot and is secured to said shank at a point adjacent the rear side of the shank. As shown in the drawings, it is pivoted at 11 by means of a suitable screw. By the placing of this 20 pivot for this yielding section well to the rear of the presser foot the yielding section will move substantially bodily in a vertical direction. The rear end 12 of the yielding section 5 is curved about this pivot 11 as a center. In the form of the invention 25 shown in Figs. 1 to 3 the rigid foot portion 4 is provided with a section 13 which extends all the way across the presser foot and lies directly in rear of the yielding section 5. The forward end of this section 30 13 is curved at 14 and this curve is also formed about the pivot 11 as a center.

The upper face of this rigid portion 13 is provided with a recess 15 extending transversely across said rigid foot portion. Mounted in this recess is a bar 16 on which the stitch fingers 17, 17 are mounted. The arm 10 overlies this rigid portion 13. A spring 18 is housed in a recess in the under 40 face of the yielding section and bears against this bar 16. The stitch fingers may readily yield vertically to accommodate a cross seam.

Directly in rear of the needle opening 9 the presser foot is provided with a cut away portion in which is located a section 19. This section extends all the way across the presser foot. It is carried by the vertically disposed members 20, 20 which slide in recesses formed in the side faces of the shank 50 1 of the presser foot. The arm 10 is located in rear of this vertical member 20. Springs 21, 21 are provided which bear on this section 19 and yieldingly press the same downward.

55 There is a slot 22 in one of the vertical members and a pin 23 located in the slot engages the walls of the slot and limits the movement of the yielding member 19. The forward end 24 of this yielding section 19 is also rounded off. This yielding section at the rear of the presser foot forms no part of the present invention per se, but is described and claimed in the application filed by Albert S. Riviere and Charles F. Rubel, Sept. 12, 1928, Serial No. 305,435.

From the above it will be apparent that when there are two layers in the fabric section at the left of the channel and one layer at the right, then the entire presser foot will yield so as to bear on the two layers and the yielding section 5 will be moved downward so that the lower face thereof is beneath the plane of the bottom of the section at the left of the slot. This causes the yielding section 5 to engage the fabric of a single thickness and possibly hold the fabric section in cooperative relation to the feed which engages the same and also holds the section with the upturned edge portions properly positioned and directed to the trimming devices. This yielding section terminates in front of the needles. The rigid member 13 is at the side of the needle opening through which the needles operate and engages the fabric sections alongside of the needles. This rigid member 13 also limits the extent to which the yielding section will be depressed when the foot is raised from the material.

A spring 25 bears on the arm 10 and tends to force the yielding section downward.

In Fig. 5 of the drawings the fabric sections are shown as consisting of two plies at the left of the channel and one ply at the right of the channel. In Fig. 6 of the drawings the fabric sections are shown as consisting of a single ply at the left of the channel and two plies at the right of the channel and under these conditions the yielding section 5 moves so that the lower face thereof is above the plane of the face of the rigid section of the foot at the left of the channel. The presser foot at the left of the channel clamps the single ply firmly against the work support and there are feed dogs for controlling the feed of the same while the yielding section at the right of the channel likewise firmly holds the two plies pressed against the work support and against the sections of the feed dog beneath the same. The entire portion of the yielding section 5 which engages the fabric sections is well in front of the pivot point 11 and this foot portion in effect moves bodily and to a uniform extent in a substantially vertical direction.

When a cross seam passes beneath the presser foot the portion thereof in front of the needles will be raised in proportion to the thickness of the cross seam. At this time the yielding section 19 will move down through the action of the spring thereon and into engagement with the fabric section in advance of the cross seam and will hold said fabric against the cloth plate or the sections of the feed dog, thus constantly controlling and feeding the same. When the cross seam has passed the needles, then this section 19 will yield and allow the front portion of the foot to move down onto the fabric following the cross seam so that this portion of the fabric is firmly clamped against the cloth.

plate or against the sections of the feed dog. The front edge of the yielding section is curved and likewise the front edge of the rigid section 13 and the front edge of the yielding section 19. This permits the fabric to move freely under these sections.

In Figs. 8 and 9 of the drawings a slightly modified form of presser foot is shown. In this form of presser foot the yielding section 5 is pivoted at 26 to the arm 10 which supports the same and the arm 10 is, in turn, pivoted at 11 to the shank of the presser foot. There is no rigid section 13 extending in rear of the yielding section 5. The yielding section 5 is located directly in front of the yielding section 19, and therefore, the yielding section 5 has been extended to a line in rear of the needles. This pivoting of the yielding section aids in the passing of the yielding section onto a cross seam. The stitch fingers are rigidly carried by the pivoted yielding section in this form of the presser foot. In this form of the presser foot there is the yielding section 5 at one side of the channel which has a substantially bodily vertically yielding movement and also a section that extends all the way across the presser foot in rear of the needles which likewise has a bodily vertically yielding movement.

It is obvious that minor changes in the details of construction and the arrangement of the parts may be made without departing from the spirit of the invention as set forth in the appended claims.

Having fully described my invention, what I claim as new and desire to secure by Letters Patent, is:—

1. The combination of horizontally disposed trimming devices, a presser foot having a channel for directing the upturned edge portions of fabric sections to said trimming devices and having means for overlapping the trimmed edge portions for stitching, means for pivotally supporting the section of the presser foot at one side of said channel on the shank of the presser foot and yielding means for moving said pivotal section downward, and means for limiting the downward movement of said yielding section, said limiting means being disposed so that the bottom face of the yielding section moves across the plane containing the bottom face of the remainder of the presser foot.

2. The combination of horizontally disposed trimming devices, a presser foot having a channel for directing the upturned edge portions of fabric sections to said trimming devices and having means for overlapping the trimmed edge portions for stitching, means for pivotally supporting the section of the presser foot at one side of said channel on the shank of the presser foot and yielding means for moving said pivotal section downward, means for limiting the down-

ward movement of said yielding section, said limiting means being disposed so that the bottom face of the yielding section moves across the plane containing the bottom face of the remainder of the presser foot, and means for 70 yieldingly supporting stitch fingers on said presser foot.

3. The combination of horizontally disposed trimming devices, a presser foot having a channel for directing the upturned edge 75 portions of fabric sections to said trimming devices and having means for overlapping the trimmed edge portions for stitching, means for pivotally supporting the section of the presser foot at one side of said channel 80 on the shank of the presser foot and yielding means for moving said pivotal section downward, means for limiting the downward movement of said yielding section, said limiting means being disposed so that the bottom 85 face of the yielding section moves across the plane containing the bottom face of the remainder of the presser foot, said presser foot having a yielding section in rear of the needles extending all the way across the presser 90 foot, means for yieldingly depressing said section, and stops for limiting the movement of said section, said stops being disposed so that the lower face of said yielding section moves across the plane of the bottom 95 of the remaining portion of the presser foot.

4. The combination of horizontally disposed trimming devices, a presser foot having a channel for directing the upturned edge portions of fabric sections to said trimming devices and having means for overlapping the trimmed edge portions, means for pivotally supporting the section of the presser foot at one side of said channel on the shank of the presser foot, a spring for moving said pivotal section downward, stops for limiting the movement of said yielding section, said stops being disposed so that the bottom of said yielding section moves across a plane containing the bottom of the section at the opposite side of the channel, the foot portion of said yielding section being disposed wholly in advance of the stitching mechanism, said presser foot having a rigid section directly in rear of said yielding section and at one side of the stitching mechanism, and means for yieldingly supporting stitch fingers on said rigid section.

5. The combination of horizontally disposed trimming devices, a presser foot having a channel for directing the upturned edge portions of fabric sections to said trimming devices and having means for overlapping the trimmed edge portions, means for pivotally supporting the section of the presser foot at one side of said channel on the shank of the presser foot, a spring for moving said pivotal section downward, stops for limiting the movement of said yielding section, said 130

stops being disposed so that the bottom of said yielding section moves across a plane containing the bottom of the section at the opposite side of the channel, the foot portion of said yielding section being disposed wholly in advance of the stitching mechanism, said presser foot having a rigid section directly in rear of said yielding section and at one side of the stitching mechanism, means for yieldingly supporting stitch fingers on said rigid section, said presser foot having a yielding section extending all the way across the foot directly in rear of the stitching mechanism, springs for yieldingly depressing said last-named section, and means for limiting the movement of said section, said limiting means being disposed so that the bottom of said section moves across the plane containing the bottom of the rigid section.

20. In testimony whereof, I affix my signature.
JAMES R. MOFFATT.
